Frank J. Busser
ATTORNEY.

UNITED STATES PATENT OFFICE.

OTTO SPAHR, OF PHILADELPHIA, PENNSYLVANIA.

SPARK PLUG.

Application filed March 13, 1920. Serial No. 365,375.

To all whom it may concern:

Be it known that I, OTTO SPAHR, a citizen of the United States, residing at Philadelphia, county of Philadelphia, and State of Pennsylvania, have invented a new and useful Improvement in Spark Plugs, of which the following is a full, clear, and exact description, reference being had to the accompanying drawings, which form a part of this specification.

My invention relates to spark plugs for use in the ignition of internal combustion engines.

The internal combustion engine is rendered more or less inefficient because of the practical impossibility of completely exhausting all of the burnt gases after the power stroke has taken place. The bulk of the burnt gas, which remains in the cylinder, collects in the end of the spark plug, mixes with the fresh gas, and renders the charge less readily burnable at the point where the spark, intended to ignite the gas, occurs. This results in a slow ignition and decreased efficiency.

In accordance with my invention, I provide a spark plug, which is so constructed as to permit of an inflow of fresh air through the plug and into the cylinder, during the intake stroke of the motor, which will clear out any burnt gas remaining in the end of the plug and about the electrodes and which will tend to neutralize the burnt gas remaining in the cylinder. The introduction of a limited amount of fresh air to the cylinder through the plug has also the result of preventing the formation of carbon in the plug and tends to homogenize the incoming mixture of fresh gas, which, upon reaching the cylinder, has tended to disintegrate to some extent.

The introduction of the air tends to keep the spark plug cool and prevents the heat from breaking the exposed end of the porcelain insulators and burning the electrode.

Gasoline may be introduced through the plug into the cylinder, for priming, and for washing or cleaning same without removing the plug from engine.

The spark plug embodying my invention is so constructed as to readily admit air during the intake stroke of the engine, but to positively prevent the escape of gas from the cylinder during the compression, power or exhaust strokes.

I will now proceed to describe a preferred embodiment of my invention with reference to the accompanying drawings, in which—

Figure 1 is a perspective view of a spark plug embodying my invention.

Figure 2 is a sectional view through the centre of the spark plug shown in Figure 1.

The body *a* of the plug is externally threaded at its lower end for insertion into an engine and internally threaded at its upper end for the reception of the packing nut *b*. The porcelain insulator *c* extends into the body of the plug and is provided with a flange *d* which rests on a shoulder *e* in the interior of the plug body. The insulator is retained in position by the packing nut *b*, which is tightened down against a washer *f* to make a tight joint.

A hollow binding post *g* extends through the centre of the insulator and is retained therein by nuts *h* and *i*, one at either end. Passages *j* are formed in the porcelain, and extend transversely to the binding post and in connection therewith. The passages extend preferably from a point just beneath the shoulder *e* and communicate with the rear end of the annular space between the body *a* and the insulator *c*.

An electrode *k* is secured in the lower end of the binding post and forms a spark gap with a second electrode *l* secured in the lower end of the body *a*.

A cylindrical casing *m*, having a central passage *n* countersunk at the upper end as at *o* is threaded to the upper end of the binding post. A disk valve *p* having cut out edges is adapted to rest in the bottom of the countersink which is tapered as shown in Figure 2. A valve seat *q*, having a central bore *r*, is threaded into the countersink and adjustable toward valve *p*. A lock nut *s* holds the valve seat *r* in its adjusted position.

In operation on the intake stroke of the engine, the valve *p* rests in the bottom of the countersink *o* and air is drawn through its cut out edges down through the hollow binding post *g* and into the end of the plug body, from which it clears out all the burnt gas and passing to the cylinder mixes with the incoming fresh charge.

The valve seat *q* may be adjusted toward the valve *p* so that the clearance between them is just sufficient to admit the desired quantity of air. When the engine is on the compression, power and exhaust strokes,

- the pressure in the cylinder extends up through the hollow end of the plug body into the hollow binding post and acts on the lower side of the valve p , raising it against seat q and preventing the escape of gas through the plug. Thus it will be seen that on the intake stroke the valve is drawn away from seat q and air enters the plug, under the influence of the suction of the engine, while at all other times during the cycles of operation of the engine, the pressure in the cylinder acts on valve p to raise it and maintain it on its seat preventing the escape of gas from the cylinder.
- Should it be desirable to prime the engine, gasoline may be injected into the top of the valve seat and will flow past the valve, through the centre of the plug and into the cylinder.
- It will be observed that there are no dead spaces communicating with the open front end of the plug, into which burnt gas can flow and collect. On the contrary, the passages j communicate with the annular space between the body α and the insulator c at the rear of said space, thus insuring that the first inflowing air will clear out all the burnt gas and that there will mix with the incoming charge no burnt gas but only fresh air that inflows after the burnt gas has been cleared out.
- By inclining the passages j at an acute angle to the axis of the plug, the distance through which a spark might jump from the metal binding post to the metal body will be increased, thus eliminating the possibility of any spark forming except between the electrodes proper.
- Having now fully described my invention, what I claim and desire to protect by Letters Patent is:
1. A spark plug for internal combustion engines comprising a hollow body, an insulator extending into said body and shaped to afford an annular recess, closed at its rear, between the insulator and the body, and a hollow binding post, the lower end of which forms an electrode, extending through said insulator, there being a passage communicating with the hollow interior of the binding post and extending through the wall of the binding post and the body of the insulator into the rear end of the annular recess between the insulator and the body.
  2. A spark plug for internal combustion engines comprising a hollow body, an insulator extending into said body and shaped to afford an annular recess, closed at its rear, between the insulator and the body, a hollow binding post extending through said insulator, and an electrode secured to the front of the binding post, there being a passage communicating with the hollow interior of the binding post and extending through the wall of the binding post and the body of the insulator into the rear end of the annular recess between the insulator and the body.
  3. A spark plug having an air channel extending therethrough and enlarged at its rear end, the lower end of the enlarged portion having tapering walls, a disc valve, having indentations on its periphery, horizontally disposed within the enlarged rear end of the air channel, and a channeled valve seat extending within the enlarged rear end of the air channel, said valve being movable downwardly to allow flow of air into the plug and upwardly against the seat to obstruct outflow of gases in the reverse direction, said valve seat being adjustable to vary the extent to which the valve recedes from its seat during inflow of air.

In testimony of which invention, I have hereunto set my hand, at Philadelphia, on this 12th day of March, 1920.

OTTO SPAHR.
